ABSTRACT

A swimming belt comprising a resilient band having a float attached to each end thereof. Each float includes a projecting yoke in which a bent portion at the end of the band is received. The bent portion has a terminal shoulder and a projection adjacent the shoulder and the bent portion extends through the yoke to lie against the outer periphery of the float such that the shoulder is received in an external groove adjacent the yoke while the projection is fitted in the yoke. The band includes a reinforcement therein between its ends in spaced relation from the floats.

DEVICES FOR TEACHING PUPILS THE ART OF SWIMMING

The present invention relates to improvements in swimming instruction aids, and more particularly to swimming belts, the purpose of which is to teach non-swimmers the art of swimming.

Such aids are known and a suitable and serviceable type comprises a resilient girdle or band, hereinafter called a band, to the ends of which are affixed floats made of cork, foam plastic or other suitable buoyant material.

Other known types of swimming belts comprise a band with floats at both ends, and also various types of swimming vests, which are tied or laced on.

Many of these known swimming aids are quite serviceable as long as they are of good quality, but show certain deficiencies when used for instructing a larger number of pupils in the art of swimming at the same time.

Most of these aids require a considerable time to put on properly, and some have a tendency to slide backwards on the swimmer who thereby risks having his head lowered under the water. This risk makes it necessary for the instructor to keep the beginners and less experienced pupils under constant vigil.

A particularly effective known swimming aid comprises a bent, resilient band carrying a float at both its ends, said band tending to bring said floats together, the band being bent to form an oval or a circle, embracing the trunk of the swimmer. This structure will tend to move in the direction of the head of the swimmer, the structure being held securely under his arms. It is easy to apply and substantially adapts to all bodybuilds and slides consistently into a correct position on the swimmer.

However, the previously known constructions of this type suffer from the disadvantage that the band has been made uniformly strong throughout which gives it, when straightened out, a tendency to yield mostly in the middle portion, which may bring the floats into an unwanted position, and in certain cases entails the risk that the swimming belt may slip or break.

The chief object of the invention is to provide a band which is provided with a reinforcement, located between the floats, said reinforcement eliminating the above-mentioned risk.

A further object of the invention is to provide an improved joining of the floats and the band, which makes it possible to detach the floats for transport or the like, but also makes sure that they do not work loose inadvertently when in use, which could cause an accident.

In the drawings:

FIG. 1 is a perspective view of a swimming belt according to the invention with a resilient band and one float, the other having been omitted for the sake of clarity;

FIG. 2 is a diagrammatic end view of a conventional of the band thereof;

FIG. 3 illustrates in a like manner the bending of a band according to the invention when stressed in the same way, and

FIG. 4 is a cross section view of a preferred embodiment of a swimming belt according to the invention.

The improvements according to the present invention will be described in detail hereinafter with reference to the drawings.

FIG. 1 illustrates an oval shaped float 1, detachably fixed to a resilient band 2. It has proved suitable to make the float 1 as a hollow body of polyethylene or of foamed plastic. The band 2, which may be subjected to rather great strain, is preferably made of HD-ethylene, nylon or similar non-corroding material.

FIG. 2 illustrates a swimming belt of a type already known with a resilient band. When this belt is put on, the band is straightened out and incurs a strong breaking tendency in the middle, which, often repeated, may cause rupture by fatigue.

FIG. 3 diagrammatically shows the improved swimming belt according to the invention, having a reinforcement 2a in the middle of the band so that the breaking tendency is counteracted. Furthermore, the band 2 according to the invention is bent at its end portions 3 is such a way, that end shoulders 4 engages grooves 5 in the floats 1 and are held into these by a force that grows when the tension in the band 2 increases.

The details of the preferred embodiment are most clearly shown in FIG. 4, which shows the floats 1 in cross section with their grooves 5, which cooperate with yokes 6 to press the bent end portions 3 of the band 2 towards the floats 1. The end portions 3 of the band 2 are provided with end shoulders 4 and also with projections 7, which help to keep the band 2 against said yokes 6. The band 2 is also provided with the reinforcement 2a at its middle.

In this way a secure connection of the floats 1 to the band 2 is attained at the same time as the risk for breaking or unwanted flexing of the band 2 is avoided.

What I claim is:

1. A swimming belt comprising a resilient band having opposite ends, and two floats, each attached to one of the ends of the band, each float including a projecting yoke for receiving on end of the band and being provided with an external groove adjacent the yoke, said band including at each end a bent portion with a shoulder, and a projection adjacent said shoulder, said bent portion extending through a corresponding yoke to lie against the outer periphery of the float with said shoulder received in part in said groove and said projection fitted in said yoke, said band including a reinforcement therein between said ends and spaced from said floats.

2. A belt as claimed in claim 1 wherein said yoke is U-shaped.
